UNITED STATES PATENT OFFICE.

RICHARD H. W. SCHMIDT, OF KANSAS CITY, MISSOURI.

WATER-FAUCET.

SPECIFICATION forming part of Letters Patent No. 662,503, dated November 27, 1900.

Application filed February 19, 1900. Serial No. 5,807. (No model.)

To all whom it may concern:

Be it known that I, RICHARD H. W. SCHMIDT, a citizen of the United States, residing at Kansas City, Jackson county, Missouri, have invented a new and useful Water-Faucet, of which the following is a specification.

My invention relates to water-faucets; and my primary object is to provide a construction whereby air is admitted to the pipe immediately after the pressure is shut off, thereby insuring thorough drainage and exemption from water freezing in the pipe.

A further object is the provision of a faucet wherein the valve may be unseated quickly and easily against the resistance of water-pressure.

To these ends the invention consists in certain novel and peculiar features of construction and combinations of parts, as will be hereinafter described, and pointed out in the appended claims, and in order that the invention may be fully understood reference is to be had to the accompanying drawings, in which—

Figure 1 is a vertical central section of a water-faucet embodying my invention, the valve being shown as seated under the pressure of the water. Fig. 2 is a detail view illustrating the valve as partly unseated.

Referring now to the drawings in detail, 1 designates the casement of the valve, provided with the internal perforated partition 2, dividing the interior of the casement into chambers 3 and 4, the latter having an outlet nozzle or spout 5. The receiving end of the casement is externally threaded, as at 6, to screw into the stand or supply pipe. (Not shown.) At the opposite end of the casement the externally-threaded neck 7 is provided, the passage of the same being in longitudinal alinement with the perforation of partition 2, and mounted upon said threaded neck is a packing-nut 8.

9 designates the valve-stem of cylindrical form and extending reciprocally through neck 7 and packing-nut 8 and having a water-tight connection with the latter, which can be maintained by screwing the nut downward as the packing wears under the frictional action thereon of the stem. At the outer end of the stem is formed a cap or handle 10 to receive the pressure of the operator's hand, though it is to be understood that any desired type of handle for forcing the stem in-

ward may be employed. The inner end of 55 the stem fits snugly and movably in the perforation of the partition 2, and its end extends obliquely to its direction of movement, as shown at 11, and formed in opposite sides of the stem are the cupped passages 12, one 60 attaining a position nearer the most advanced point of the end of the stem than the other for a purpose which will hereinafter appear.

13 designates a screw-bolt depending axially from the valve-stem through the partition-perforation and provided at its lower end with an angular head 14 by preference.

The valve proper is constructed as follows:

15 designates a washer mounted loosely upon the bolt and adapted to seat squarely 70 up against the partition 2 and prevent water from passing between it and the partition and up through the perforation of the latter, and in order that this washer may be as strong and durable as possible I prefer to 75 make it of fiber instead of rubber, though the latter of course may be employed.

16 designates a metallic washer also fitting loosely on the bolt and interposed between the head of the latter and the fiber washer 80 and provided with a depending annular externally-threaded flange 17, loosely enveloping the head of the bolt.

18 designates an inverted metallic cap screwed upon the depending flange 17 of the 85 metallic washer, and in order that the joint between said metallic washer and cap may be absolutely water-tight and grow more perfect with service said parts are preferably made of brass, it being well known that the frictional action of brass against brass will effect a perfect joint by reason of one part adapting itself to the other.

From the foregoing it will be seen that the valve fitting loosely upon the bolt is permitted direct reciprocal movement thereon, but may tilt and accommodate itself to the oblique inner end of the valve-stem. When the pressure is off, the valve is automatically and immediately unseated under the pressure of air 100 entering chamber 3, assisted by the gravitational tendency of the valve, thereby admitting air to the stand or supply pipe and by effecting a thorough drainage of the latter eliminating all chance of the water freezing in the 105 pipe. When the water is turned on again, it instantly forces the valve against the seat and prevents the escape of water through the

discharge spout or nozzle. When water is desired, the operator presses upon the handle 10, which results first in forcing the stem inward from the position shown in Fig. 1 until 5 the most advanced point of its oblique end is in contact with the fibrous washer. The continued pressure then causes the washer to fulcrum against the partition 2 at a point diametrically opposite the point of engagement 10 with said stem, which results in a very gradual exposure of the partition-perforation and the lower end of the most advanced passage 12 in the stem to the water in chamber 3, which of course relieves the pressure in the 15 pipe materially and permits the continued operation of the valve-stem to take place without difficulty, said operation being continued by preference until the oblique end of the stem protrudes entirely into chamber 3, and 20 the valve is canted upon the bolt 13, the washer 15 bearing squarely against the oblique end, and consequently occupying a position at an angle to the stem. When the pressure is removed from handle 10, the water will reseat 25 the valve and force the valve-stem back to the position shown in Fig. 1.

It will thus be seen that by providing the stem with an oblique inner end the operator is given a leverage on the water under pressure 30 equal to the distance between the point of contact on the stem with washer 15 and the periphery of the latter at a point diametrically opposite its point of contact with the stem, which leverage enables the operator to 35 unseat the valve with much greater ease and despatch than if the whole power of the water-pressure had to be overcome by forcing the valve bodily away from its seat. In the former case the operator not only has the leverage to displace the water, but need displace it only very slightly, while in the latter case a considerable volume of water, comparatively viewed, must be displaced in the 40 movement of the valve bodily from its seat to admit the water simultaneously to the perforation of the partition from all sides of the washer 15.

A defect common to all faucets with which I am familiar and remedied in this one is the 45 failure to admit air to the pipe after the pressure is cut off, the admission of air being desirable to effect the thorough drainage of the pipe and eliminate all chance of water freezing therein.

It is to be understood, of course, that while I have illustrated and described the preferred embodiment of the invention I reserve the right to make such changes in the form, proportion, detail construction, or arrangement 50 of the parts as shall not involve a departure from the spirit and scope or sacrifice any of the advantages embraced in the construction recited by the appended claims.

Having thus described the invention, what 55 I claim as new, and desire to secure by Letters Patent, is—

1. A water-faucet, comprising, a casement

having a perforated partition, a rigid valve-stem projecting into the casement and through the partition-perforation, and a valve carried 70 loosely by said stem so as to reciprocate and tilt thereon and adapted to be seated and close the perforation of the partition by the pressure of the water and unseated when the pressure is shut off, substantially as described. 75

2. A water-faucet, comprising a casement having a perforated partition, a valve-stem mounted in the casement and projecting into the perforation of the partition, and having its inner end more advanced at one side of 80 its center than at any other point, and provided with an extension of smaller diameter which projects beyond said advanced point on the end of the stem and through the partition-opening, and a valve carried loosely by 85 said extension and adapted to reciprocate and tilt thereon and be forced against the perforation of the partition by the pressure of the water and to be unseated gradually by the valve-stem or by gravity or atmospheric pressure when the water is shut off, substantially 90 as described.

3. A water-faucet, comprising a casement, having a perforated partition, a valve-stem projecting movably therein and provided with 95 an extension of smaller diameter having a head or enlargement at its inner end, and a valve mounted upon said extension so as to reciprocate thereon or tilt at an angle thereto, and adapted to be unseated when the pressure is shut off, and rest upon the enlargement of said extension, substantially as described. 100

4. A water-faucet, comprising a casement having a perforated partition, a valve-stem 105 projecting movably therein, a bolt projecting from the stem to the opposite side of the partition, and a valve mounted upon said bolt, and consisting of a compressible washer, a metallic washer inward of the same, and a 110 metallic cap screwed to the metallic washer and completely enveloping the inner end of the bolt, substantially as described.

5. A water-faucet, comprising a casement having a perforated partition, a valve-stem 115 projecting movably therein, a bolt projecting from the stem to the opposite side of the partition and provided with a head, and a valve mounted upon said bolt, and consisting of a compressible washer, a metallic washer between the partition and the head of the bolt, the bolt-passage of the latter being of smaller 120 diameter than the head of the bolt to prevent the dislocation of the washer, and a metallic cap loosely enveloping the head of the bolt 125 and screwed to said metallic washer, substantially as described.

In testimony whereof I affix my signature in the presence of two witnesses.
